(57) **CLAIM**

The ornamental design for a set of microphone, receiver and charging case as shown and described.

DESCRIPTION

FIG. 1 is a front, right and top perspective view of a charging case of a set of microphone, receiver and charging case of FIG. 2 showing my new design, shown separately for ease of illustration.

FIG. 2 is a front, left and top perspective view thereof.

FIG. 3 is a rear, left and bottom perspective view thereof.

FIG. 4 is a front elevation view thereof.

FIG. 5 is a rear elevation view thereof.

FIG. 6 is a left side elevation view thereof.

FIG. 7 is a right side elevation view thereof.

FIG. 8 is a top plan view thereof.

FIG. 9 is a bottom plan view thereof.

FIG. 10 is an enlarged view of detail 10 in FIG. 1.

FIG. 11 is an enlarged view of detail 11 in FIG. 1.

FIG. 12 is a front, left and top perspective view of the microphone of the set of microphone, receiver and charging case of FIG. 32, shown separately for ease of illustration.

FIG. 13 is a rear, right and bottom perspective view thereof.

FIG. 14 is a front elevation view thereof.

FIG. 15 is a rear elevation view thereof.

FIG. 16 is a left side elevation view thereof.

FIG. 17 is a right side elevation view thereof.

FIG. 18 is a top plan view thereof.

FIG. 19 is a bottom plan view thereof.

FIG. 20 is an enlarged view of detail 20 in FIG. 12.

FIG. 21 is an enlarged view of detail 21 in FIG. 13.

FIG. 22 is a front, right and top perspective view of the receiver of the set of microphone, receiver and charging case of FIG. 32, shown separately for ease of illustration.

FIG. 23 is a rear, left and bottom perspective view thereof.

FIG. 24 is a front elevation view thereof.

FIG. 25 is a rear elevation view thereof.

FIG. 26 is a left side elevation view thereof.
